(57) **CLAIM**

The ornamental design for a single bucket organizer, as shown and described.

DESCRIPTION

FIG. 1 is a perspective view of the invention.

FIG. 2 is a front view of the invention.

FIG. 3 is a rear view of the invention.

FIG. 4 is a right side view of the invention; the left side view is a mirror image.

FIG. 5 is a top plan view of the invention; and,

FIG. 6 is a bottom plan view of the invention.

The broken lines are for the purpose of illustrating the environment of the design only and form no part of the claimed design.
